(57)

CLAIM

The ornamental design for a feeder-teether, as shown and described.

DESCRIPTION

FIG. 1 is a top, right perspective view of a feeder-teether showing my new design.

FIG. 2 is a top plan view thereof.

FIG. 3 is a left view thereof.

FIG. 4 is a front view thereof.

FIG. 5 is a right view thereof.

FIG. 6 is a rear view thereof.

FIG. 7 is a bottom plan view thereof; and,

FIG. 8 is a bottom, rear perspective view thereof.

The broken lines in the drawings depict portions of the feeder-teether that form no part of the claimed design.
